TRAY FOR MEDICAL EQUIPMENT

Donald A. Hamilton, Burbank, Calif., assignor to Pharma-seal Laboratories, Glendale, Calif., a corporation of California

Filed Dec. 28, 1964, Ser. No. 83,188

Term of patent 14 years

(Cl. D83—1)

FIG. 1.

FIG. 2.

FIG. 3.

FIG. 4.

FIG. 7.

FIG. 5.

FIG. 6.

FIG. 8.

FIG. 9.

FIG. 10.

FIG. 11.

FIG. 13.

FIG. 12.

FIG. 14.

FIGURE 1 is a perspective view of the tray;
FIGURE 2 is a top plan view of the tray;

FIGURE 3 is a rear elevational view of the tray;
FIGURE 4 is a front elevational view of the tray;
FIGURE 5 is a left side elevational view of the tray;
FIGURE 6 is a right side elevational view of the tray;
FIGURE 7 is a bottom plan view of the tray;

FIGURE 8 is a sectional view of the tray taken along line 8-8 of FIGURE 2;

FIGURE 9 is a sectional view of the tray taken along line 9-9 of FIGURE 2;

FIGURE 10 is a sectional view of the tray taken along line 10-10 of FIGURE 2;

FIGURE 11 is a sectional view of the tray taken along line 11-11 of FIGURE 2;

FIGURE 12 is a sectional view of the tray taken along line 12-12 of FIGURE 2;

FIGURE 13 is a fragmentary enlarged sectional view of the tray taken along line 13-13 of FIGURE 2; and

FIGURE 14 is a sectional view of the tray taken along line 14-14 of FIGURE 2.

The dotted lines in FIGURES 1, 2 and 7 for indicating catheter sizes are for illustrative purposes only.

I claim:

The ornamental design of a tray for medical equipment, as shown and described.
